(57) **CLAIM**

The ornamental design for a cup holder, as shown and described.

DESCRIPTION

FIG. 1 is a perspective view of a cup holder showing my new design.

FIG. 2 is a front elevational view of the cup holder of FIG. 1;

FIG. 3 is a rear elevational view of the cup holder of FIG. 1;

FIG. 4 is a top elevational view of the cup holder of FIG. 1;

FIG. 5 is a bottom elevational view of the cup holder of FIG. 1;

FIG. 6 is a right side elevational view of the cup holder of FIG. 1;

FIG. 7 is a left side elevational view of the cup holder of FIG. 1; and,

FIG. 8 is perspective view of the cup holder of FIG. 1, shown in a representative environment.

The features shown in broken lines are environment only and not part of the claimed design.
